United States Patent

Des. 235,441
Patented June 17, 1975

235,441

BASIC MEASUREMENT EDUCATIONAL BOARD

Charles G. Valentine, Stamford, Conn., assignor to
Xerox Corporation, Stamford, Conn.

Filed Apr. 27, 1973, Ser. No. 355,224

Term of patent 14 years

Int. Cl. D19—07

U.S. Cl. D19—62

FIG. 2

FIG. 1 is a left perspective view of a basic measurement educational board showing my new design; and
FIG. 2 is a right perspective view thereof.

FIG. 2 is a right perspective view thereof.
The rear of the basic measurement educational board
not shown is plain and unornamented.

I claim:

The ornamental design of a basic measurement educational board, substantially as shown and described.
